UNITED STATES PATENT OFFICE.

HENRY H. HEUERMAN AND HENRY HUNTEMAN, OF HILLSBORO, OREGON.

WRENCH.

1,097,096.

Specification of Letters Patent. Patented May 19, 1914.

Application filed September 30, 1913. Serial No. 792,631.

To all whom it may concern:

Be it known that we, HENRY H. HEUERMAN and HENRY HUNTEMAN, citizens of the United States, residing at Hillsboro, in the county of Washington and State of Oregon, have invented certain new and useful Improvements in Wrenches, of which the following is a specification.

The wrench which is the subject matter of the present application for patent is designed for grinding valves on their seats, it being constructed to grip the valve to enable the same to be rotated on its seat for the purpose stated.

The object of the invention is to provide a simple and efficient wrench of the kind stated, and one having novel and improved means for adjusting the jaws to enable the wrench to be applied to different sized valves.

In order that the invention may be better understood, reference is had to the accompanying drawing, in which—

Figure 1 is an elevation of the wrench. Fig. 2 is a vertical section on the line 2—2 of Fig. 1. Fig. 3 is an end view of the wrench. Fig. 4 is a horizontal section on the line 4—4 of Fig. 1.

Referring specifically to the drawing, the shank 5 of the wrench is a stem of suitable length having at one end a cylindrical enlargement 6 forming the wrench head. The other end of the shank has a tang 7 for insertion into a suitable tool whereby the valve to be ground is turned after supplying the wrench to the latter.

The head 6 has a transverse passage 8 in which are slidably mounted, side by side, the shanks 9 of valve engaging studs 10. The studs are on one end of the shanks, and said ends project from opposite sides of the head to locate the studs outside the latter on opposite sides thereof. The studs may be spread or brought closer together by sliding the shanks thereof in opposite directions. This adjustment is effected by a pinion 11 which is in mesh with rack-teeth 12 on the shanks. The rack-teeth are on the bottom of the shanks and spaced a sufficient distance from the contiguous surfaces of the shanks to permit the pinion to seat beneath the shanks between the rack-teeth of the respective shanks, which latter are therefore on

opposite sides of the pinion, so that when the pinion is rotated, the shanks are caused to 55 travel simultaneous in opposite directions.

The pinion 11 is carried on the inner end of a stud 13 rotatably mounted in a central aperture in the end of the head 6, said aperture opening into the passage 8. The outer 60 end of the stud has a transverse kerf 14 in order that a screw driver may be used for turning the stud to rotate the pinion.

The studs 10 extend from depending end portions 15 of the shanks 9, and in order that 65 the studs may be drawn as closely together as possible, the opposite sides of the head have recesses 16 in which the end portions 15 seat at the limit of the inward adjustment of the studs.

In order to securely lock the shanks 9 so that the adjustment of the studs 10 may not be disturbed, the head is split longitudinally from the shank 5 to the passage 8, as indicated at 17. This split is parallel to the 75 plane of the shanks 9, and they are clamped together in the passage 8 in adjusted position upon tightening up a screw 18 passing through the split portions of the shank 5. This screw passes loosely through that 80 portion of the head which is on one side of the slit, and it is threaded into that portion of the head on the other side of the slit. Thus, when the screw is turned in one direction, the two portions of the head 85 are drawn together to clamp the shanks 9, and when the screw is turned in the opposite direction, said portions spread and release the shanks 9.

We claim:

A wrench comprising a shank having a head provided with a transverse passage and a longitudinal split extending from said passage rearward to the shank, said head also having a central longitudinal 95 aperture extending from its outer end to the passage, means for drawing the split portions of the head together, shanks slidably mounted side by side in the transverse passage and projecting from opposite sides 100 of the head, the projecting ends of the shanks having spanner studs, rack teeth on the bottom of the slidably shanks, the rack teeth of the respective shanks being spaced apart, a pinion mounted in 105 the transverse passage beneath the

shanks and located between the rack teeth thereof and in mesh therewith, and means for operating the pinion, said means comprising a stud mounted in the aforesaid aperture and projecting from the outer end of the head, the inner end of the stud being connected to the pinion.

In testimony whereof we affix our signatures in presence of two witnesses.

HENRY H. HEUERMAN.
HENRY HUNTEMAN.
